2 SHEETS—SHEET 2.

UNITED STATES PATENT OFFICE

CHARLES R. HALL, OF MONROETON, PENNSYLVANIA, ASSIGNOR OF ONE-FOURTH TO
ROBERT F. HALL, OF MONROETON, PENNSYLVANIA.

CRANKING DEVICE FOR INTERNAL-COMBUSTION ENGINES.

974,136.

Specification of Letters Patent. Patented Nov. 1, 1910.

Application filed September 22, 1909. Serial No. 519,052.

To all whom it may concern:

Be it known that I, CHARLES R. HALL, citizen of the United States, residing at Monroeton, in the county of Bradford and State of Pennsylvania, have invented certain new and useful Improvements in Cranking Devices for Internal-Combustion Engines, of which the following is a specification.

10 This invention relates broadly to internal combustion engines and refers particularly to an attachment to be applied to the same for the purpose of preventing the impulse of the back firing of the engine to the crank handle when starting the same.

An object of this invention is to provide an attachment to a gas engine by means of which the gas engine may be manually cranked or started, and through the medium 20 of which the back firing of the engine will disconnect the crank arm from the crank shaft of the engine, thereby insuring the safety of the operator in starting the engine.

The invention further contemplates the provision of an attachment of this character which is of simple form and which comprises but few parts, so that the same may be readily applied to gas engines of common construction without the necessity of forming the crank shaft or other parts of the engine for adaptation to the attachment.

The invention has for a still further object the provision of a cranking attachment which is so formed that the same will freely 35 operate when turning the engine in the direction to start the same, while should the engine back fire, the reverse rotation of the crank shaft will cause the engagement of a clutch, which is connected to the improved 40 attachment, and will permit of the gradual stopping of the engine and at the same time bind the crank handle from a reverse movement, thus preventing the jerking of the crank handle from the operator's hand or 45 from injuring the operator in any manner.

For a full understanding of the invention and the merits thereof and also to acquire a knowledge of the details of construction, reference is to be had to the following description and accompanying drawings, in which:

Figure 1 is a side elevation of a gas engine disclosing the improved cranking mechanism as applied to the same, the figure be-

ing disclosed partly in section; Fig. 2 is a 55 longitudinal section through the improved cranking mechanism detached from the engine; Fig. 3 is a transverse section through the cranking attachment on the line 3-3 of Fig. 2; and, Fig. 4 is a detailed and enlarged sectional view through the clutch drum disclosing the disks of the clutch as separated from the same.

Corresponding and like parts are referred to in the following description and indicated in all the views of the drawings by the same reference characters.

Referring particularly to the drawings, the numeral 10 designates an internal combustion engine having a crank shaft 11 which extends forwardly from the same and upon which is secured a ratchet sleeve 12. The teeth of the ratchet sleeve 12 are extended outwardly in the direction of the crank shaft 11 and coöperate with a second 75 ratchet sleeve 13 mounted upon a stub shaft 14 connected to the improved cranking mechanism. The stub shaft 14 is extended into a drum 15 and is provided with spaced 80 disks 16, the same comprising circularly formed and flattened metallic members having keyways 17 cut in the inner edges of the same for the reception of keys 18, which are splined to the stub shaft 14. In this manner the disks 16 are retained in rigid 85 relation upon the stub shaft 14 and are caused to rotate therewith. The drum 15 is provided with disks 19 and 20, the disk 20 being provided in its periphery with keyways 21 for the reception of keys 22, which 90 are carried by the drum for the purpose of locking the disk 20 rigidly with relation to the drum.

From Fig. 2 of the drawings it will be noted that the disk 20 is interposed between 95 the disks 16 and is engaged at its opposite faces against the adjacent faces of the disks 16. The disk 19 is provided in its periphery with longitudinal threads which mesh with corresponding threads formed in the outer 100 end of the drum 15, and through the medium of which threads, the disk 19 is retained within the drum 15 and against the outer disk 16. Depressions 23 are formed in the outer face of the disk 19 for the reception of a spanner wrench, or a like implement, employed for removing and positioning the disk 19 within the drum 15. The 105

- drum 15 is converged at its inner end to form a neck 24 which is suitably apertured for the reception of a pin 25 which is extended diametrically through the neck 24 and through a corresponding aperture formed through the forward end of an operating shaft 26, which is extended into the neck 24 and terminated adjacent the inner end of the stub shaft 14.
- 10 The operating shaft 26 is extended through a plate 27 which is clamped to a frame 28 which supports the internal combustion engine 10, and the plate 27 forms a bearing for supporting the outer end of the shaft 26. Forwardly extended from the plate 27, and preferably integrally formed therewith, as is disclosed in the drawings, is a cylinder 29, the same being engaged about the neck 24 to permit of the free rotation of the neck 24 therein. A collar 30 is carried loosely upon the operating shaft 26 adjacent the neck 24, and is provided at diametrically opposite points with keys or beads 31 for engagement in grooves 32 formed longitudinally in the forward end of the cylinder 29 to permit of the longitudinal sliding of the collar 30 and to lock the same from rotative movement relative to the cylinder 29.
- 15 30 The collar 30 is provided with a plurality of ratchet teeth in its forward face which co-act with a like plurality of ratchet teeth which are formed upon the rear end of the neck 24 for the purpose of locking the neck 24 upon the backward rotation of the same by engagement with the collar 30. The operating shaft 26 carries an abutment 33 which is in the form of a disk and which is keyed to the shaft 26 through the medium of a pin 34 which is extended diametrically through the abutment 33 and the shaft 26. A helical spring 35 is disposed about the shaft 26 between the collar 30 and the abutment 33 for the purpose of frictionally holding the collar 30 against the inner end of the neck 24 to insure the engagement of the teeth of the two members upon the reverse motion of the neck 24. In the usual manner a spring 36 is employed which is positioned between the frame 28 and the head 37 of a crank arm 38, the head 37 being secured to the outer extremity of the operating shaft 26. The spring 36 is provided for the purpose of normally retracting the cranking device to hold the ratchet sleeves 12 and 13 out of engagement with one another.
- 20 25 In the operation of the improved device when it is desired to start the gas engine the crank arm 38 is grasped in the hand and rotated in the direction in which the engine is to be run, which is generally in a rotation to the right. When the arm 38 is rotated the shaft 26 is carried therewith, which imparts a rotation to the drum 15. As the drum 15 is rotated the disks 19 and 20 are carried

therewith and by their frictional engagement cause the rotation of the disks 16, whereby the stub shaft 14 is rotated and caused to carry the ratchet sleeve 13 therewith. During the rotation of the crank arm 38 the same is forced inwardly to carry the operating shaft 26 longitudinally through the plate 27, whereby the ratchet sleeve 13 is abutted with the ratchet sleeve 12 and is thereby connected to the crank shaft 11 of the engine. Should the engine tend to back fire or a premature explosion occur, and the crank shaft be given an impulse in the reverse direction, the ratchet sleeves 12 and 13 will be carried with the crank shaft 11 and rotate the disks 16 together with the stub shaft 14, whereby the drum 15 is given a slight reverse movement. Simultaneously with this operation the teeth upon the neck 24 lock with the teeth formed upon the collar 30 and tend to rotate the collar 30. The collar 30 however, is locked from rotation by the provision of the keys 31 which are engaged in the grooves 32, whereby the neck 24 is prevented from further rotation and the drum 15 is held rigidly together with the disks 19 and 20. Should the force of the explosion be of sufficient strength the disks 16, which are carried by the stub shaft 14, will slide between the disks 19 and 20 and will by their friction bring the crank shaft 11 to a standstill upon the expenditure of the impulse which is imparted to the same by the premature explosion. As the operating shaft 26 is carried by the neck 24, which is locked from backward rotation, the shaft 26 is held in an inactive position and consequently the handle 38 is prevented from a backward movement. The disks 16, and 19 and 20 are engaged with one another with sufficient force to prevent the slipping of the same under the ordinary cranking action of the engine, but which are permitted to yield upon the increased force of the premature explosion or back firing. The grooves or keyways 32 are formed in the cylinder 29 for the purpose of admitting of the following of the collar 30 against the neck 24 when the operating shaft 26 is forced forwardly toward the engine against the tension of the return spring 36.

Having thus described the invention what is claimed as new is:

1. In a cranking mechanism the combination with an internal combustion engine having a crank shaft and a ratchet sleeve mounted thereon, of a stub shaft disposed adjacent said crank shaft, a second ratchet sleeve carried by said stub shaft for interlocking engagement with said first ratchet sleeve, a plurality of disks disposed in spaced relation upon said stub shaft, a drum concentrically disposed about said stub shaft, a plurality of disks disposed in spaced relation in said drum for alternate engage- 125

ment between said disks on said stub shaft, an operating shaft rigidly carried by said drum, a cylinder disposed about said operating shaft, a collar slidably disposed with 5 in said cylinder, keys carried by said collar for retaining the same from rotation, teeth disposed upon said collar, teeth mounted on said drum for engagement with the teeth on said collar, and means disposed in said cylinder for yieldably holding said collar against said drum.

2. The combination with an internal combustion engine having a crank shaft, of a stub shaft disposed in longitudinal alinement adjacent said crank shaft, ratchet sleeves carried by said crank shaft and said stub shaft for interlocking engagement, a plurality of disks carried by said stub shaft, an operating shaft arranged in longitudinal alinement adjacent said stub shaft, a drum rigidly carried by said operating shaft and located about said stub shaft, pluralities of disks disposed in alternate arrangement within said drum and carried by said drum 25 and said stub shaft, a neck formed on said drum, a cylinder loosely disposed about said neck, a collar slidably mounted in said cylinder about said operating shaft, series of teeth mounted in the adjacent faces of said 30 neck and said collar, an abutment formed on said operating shaft, and a spring located between said abutment and said collar for retaining said collar against said drum.

3. A cranking mechanism including a crank shaft, a stub shaft disposed in interlocking relation with said crank shaft, disks carried by said stub shaft, an operating shaft disposed adjacent said stub shaft, disks carried by said operating shaft for frictional 40 alternate engagement between said disks on said stub shaft, and means carried by said operating shaft for locking the same upon the reverse rotation thereof.

4. A cranking mechanism including a

crank shaft, a stub shaft mounted adjacent 45 said crank shaft, interlocking ratchet sleeves carried by said shafts, an operating shaft located in longitudinal alinement with said stub shaft, a drum carried by said operating shaft, interfitting disks carried by said stub shaft and said drum for frictional engagement with one another, a collar disposed about said operating shaft, a cylinder located about said operating shaft and said collar, keys carried by said collar for engagement with said cylinder to retain said collar against rotation, a spring carried by said operating shaft for engagement with the collar to abut the same with said drum, teeth carried by said collar and said drum 60 for interlocking engagement, and a crank arm mounted upon the inner end of said operating shaft for imparting rotation to the same.

5. In a cranking mechanism, the combination with an internal combustion engine having a crank-shaft, of a stub shaft arranged in alinement with said crank-shaft, intermeshing ratchet sleeves on said shafts, a drum concentrically disposed about said stub 70 shaft, disks mounted about said stub shaft in said drum and being alternately keyed to said stub shaft and to said drum, an operating shaft rigidly carried by said drum, a cylinder engaged about said operating 75 shaft, a collar loosely disposed about said operating shaft and keyed to said cylinder, interlocking teeth formed upon said drum and said collar, and a spring carried in said cylinder and against said collar to press said 80 collar against said drum.

In testimony whereof I affix my signature in presence of two witnesses.
